UNITED STATES PATENT OFFICE.

TIMOTHY A. WELCH, OF SAYRE, PENNSYLVANIA.

SAFETY DEVICE FOR BOLT-MACHINES.

1,111,424.

Specification of Letters Patent. Patented Sept. 22, 1914.

Application filed October 4, 1913. Serial No. 793,320.

To all whom it may concern:

Be it known that I, TIMOTHY A. WELCH, a citizen of the United States, residing at 313 North Lehigh avenue, Sayre, in the 5 county of Bradford and State of Pennsylvania, have invented certain new and useful Improvements in Safety Devices for Bolt-Machines; and I do hereby declare the following to be a full, clear, and exact description 10 of the invention, such as will enable other skilled in the art to which it appertains to make and use the same.

The object of this invention is to provide 15 a safety device for a bolt machine adapted to yield when the bolt blank is improperly placed or when a foreign substance falls between the dies thereby protecting the latter against breakage or mutilation.

Another object is to provide means for 20 locking the yieldable safety device against operation while the dies of the machine are being properly fed.

In the accompanying drawing wherein is 25 shown an approved embodiment of my invention, Figure 1, represents a top plan view of a bolt making machine of ordinary construction, showing the application of my improved safety device attached thereto. Fig. 2, represents a fragmentary side elevation of the machine and safety device. Fig. 3, represents a fragmentary vertical transverse sectional view through the movable die block and yieldable operating means therefor. Fig. 4, represents a top plan view of 30 the wedge member. Fig. 5, represents a side elevation thereof. Fig. 6, represents a front elevation thereof. Fig. 7, represents a fragmentary detail view in side elevation of the toggle head. Fig. 8, is a sectional view on 35 the line 8—8 of Fig. 7. Fig. 9, represents a sectional view on the line 9—9 of Fig. 7. Fig. 10, represents a side elevation of the loose block. Fig. 11, represents a plan view thereof, and Fig. 12, represents a plan view 40 of one of a pair of guide members for one of the movable parts of the safety device.

Referring to the drawing in detail, 45 indicates the frame of a modern type of bolt making machine, the operative parts of which are driven by the crank shaft 16, over 50 which are connected pitmen 17. One of the pitmen is connected as usual with the heading die 18, while the other pitman is connected with the toggle head 19 which latter is 55 clearly illustrated in Figs. 7, 8, and 9. The stationary die is indicated at 20, and the mov-

able die at 21, the latter being connected to the toggle head 19 through the toggle links 22, of the two-way toggle block 23, and the die block 24, in the usual manner. The other 60 link of the toggle block 23, is connected with a loose block 25 having an inclined face 26 abutting the similarly inclined face of the wedge member 27, having upwardly extending rods 28 working through a suitable 65 bracket 29 against the tension of springs 30.

A pair of guide members 31 are secured to the top of the frame 15 and extend transversely of the latter and are adapted to guide the movement of the lock bar 32, which 70 in its normal position or when the dies are open is removed from the path of the wedge member 27. The inner end of a threaded rod 33 is pivoted at 34 to the movable die holder 24, extends through the locking member 32 and is provided upon opposite sides 75 of the latter with nuts 35. A spring 36 is disposed over the rod 33 between the locking member 32 and outer nut 35, so as to normally hold said locking member inwardly 80 against the inner nut 35. The wedge member 27 is provided with a suitable slot 37 for accommodating the rod 33.

In the operation of the machine, the blanks 85 are fed in the usual manner to the dies 18, 20, and 21, and the machine is driven from a suitable source of power. As the dies close over a properly placed blank the locking member 32 is moved into locking position 90 over the wedge member 27, as shown in Fig. 95 3, preventing said wedge member from raising. However, should a blank be improperly gripped, it is obvious that the resistance to the movement of the dies and toggle mechanism will be nearly simultaneous with its initial closing movement, and the wedging member 27 will be pushed upwardly by the loose block 25 against the tension of the spring 30, before the locking member 32 moves thereover. In this way the moving 100 die 21 will be prevented from closing over the improperly placed blank and possible injury thereto is also prevented. As the dies are again opened, the blank drops therefrom and the spring actuated wedge member 27 105 assumes its initial position as clearly shown in Fig. 3, for the next operation. It will be understood that the nuts 35 may be adjusted so as to accommodate interchanging and adjusting of the dies and other parts of the 110 machine.

Having thus fully described my invention

what I claim as new and desire to secure by Letters-Patent is;

1. In a device of the class described, a frame, a stationary die, a movable die, a reciprocating member slidable in said frame, a two way toggle block, connected to said reciprocating member, one link of said toggle block being connected to said movable die, yieldable means also connected to the opposite link of said toggle block, and adjustable means for locking said yieldable means against operation.
2. In a device of the class described a frame, a stationary die, a movable die, a reciprocating member, capable of sliding movement in said frame, a two way toggle block, connected to said reciprocating member, means for connecting said toggle block with said movable die in one direction, yieldable means connected with said toggle block in the other direction, and means for locking said last named means against yielding.
3. In a device of the class described, a frame, a stationary die, a movable die, a reciprocating member, slidably mounted in said frame and toggle block pivoted to said reciprocating member, means for connecting said toggle block in one direction with said movable die, yieldable means connected with said toggle block in the other direction and movable means for locking said yieldable means against operation.
4. In a device of the class described, a frame, a stationary die, a movable die, a reciprocating member slidably mounted upon said frame, a two way toggle block pivoted to said reciprocating member, means for connecting said toggle block with said movable die, yieldable means also connected to said toggle block but oppositely to said movable die, and means to lock said yieldable means against operation, subsequent to the initial closing movement of said movable die.
5. In a device of the class described, a frame, a stationary die, a movable die, a reciprocating member mounted on said frame, a two way toggle block pivoted to said reciprocating member, means for operatively connecting said toggle block to said movable die in one direction, yieldable means connected with said toggle block in the other direction, and positively actuated means for locking said yieldable means

against operation, subsequent to the initial closing of said yieldable die.

6. In a device of the class described, a frame, a stationary die, a movable die, a reciprocating member mounted on said frame, a two way toggle block pivoted to said reciprocating member, means for operatively connecting said toggle block to said movable die in one direction, yieldable means connected with said toggle block in the other direction, and means operatively connected with said movable die for locking said yieldable means against operation.

7. In a device of the class described, a frame, a stationary die, a movable die, a reciprocating member mounted on said frame, a two way toggle block pivoted to said reciprocating member, means for operatively connecting said toggle block to said movable die in one direction, yieldable means connected with said toggle block in the other direction, locking means provided for holding said yieldable means against operation, and means operatively connecting said locking means with said movable die.

8. In a device of the class described, a frame, a stationary die, a movable die, a reciprocating member mounted on said frame, a two way toggle block pivoted to said reciprocating member, means for operatively connecting said toggle block to said movable die in one direction, yieldable means connected with said toggle block in the other direction, means for locking said yielding means against operation, and means adjustably connecting said locking means with said movable die.

9. In a device of the class described, a frame, a stationary die, a movable die, a reciprocating member mounted on said frame, a two way toggle block pivoted to said reciprocating members, means for operatively connecting said toggle block to said movable die in one direction, yieldable means connected with said toggle block in the other direction, and means adjustably and yieldably connecting said locking means with said movable die.

In testimony whereof I have signed my name to this specification in the presence of two subscribing witnesses.

TIMOTHY A. WELCH.
